UNITED STATES PATENT OFFICE.

WALTER WATSON, OF FAYETTEVILLE, NORTH CAROLINA.

TURPENTINE-TOOL.

SPECIFICATION forming part of Letters Patent No. 498,593, dated May 30, 1893.

Application filed July 11, 1892. Serial No. 439,587. (No model.)

To all whom it may concern:

Be it known that I, WALTER WATSON, of Fayetteville, in the county of Cumberland and State of North Carolina, have invented a new 5 and useful Improvement in Turpentine-Tools, of which the following is a specification.

This invention relates generally to turpentine tools, and particularly to a combination tool, the object of the invention being to provide a double hacker and puller in a single instrument, whereby time, labor, material and money are saved, and with this object in view my invention consists in the peculiar construction of the several parts, and their novel 15 combination and arrangement, all of which will be fully described hereinafter, and pointed out in the claims.

Figure 1 is a perspective view of my improved tool. Fig. 2 is a vertical section of 20 the same and Fig. 3 is a horizontal section.

In carrying out my invention I employ a shank A and blade B. The shank A is provided with the usual stud a at its lower end, and in its body is produced an aperture a' to 25 permit attachment to a handle, as shown and described in my prior Patent No. 327,207, dated September 29, 1885. The upper end of the shank is formed with a flat rectangular head or plate A', and at the juncture of the 30 head and shank is produced a transverse seat A², said seat being provided with a retaining flange A³, thus producing a groove between the flange and head which is adapted to receive the blade B, said blade resting upon the 35 seat as clearly shown. A transverse rib A⁴ is formed at the upper end of the head, and it will be observed that the blade is secured upon the head between the seat and rib by means of a bolt b passed centrally through 40 the head and plate. The blade B has its upper and lower edges sharpened as shown at B' and its ends are rounded and sharpened as shown at B². These sharpened and rounded ends are also bent back toward each other 45 providing both "hackers" and pullers at each end of the blade. The blade is readily detachable and reversible and from this it will be seen that I provide four hackers and four pullers in a single device. It will also 50 be noted that the blades being easily attached and detached, can be quickly removed and replaced when worn. The seat and rib receive

a great deal of the strain applied to the blade, thus relieving the bolt, keeping the blade straight, and dispensing with a number of 55 bolts which weaken the contrivance.

Having thus described my invention, what I claim as new, and desire to secure by Letters Patent, is—

1. As an improved article a combined hacker and puller consisting of a flat blade having its ends curved or bent toward each other, said blade being attached to a shank or handle substantially as shown and described. 60

2. As an improved article, a puller blade, 65 having sharp edges and ends said ends being bent to provide hackers at each end substantially as shown and described.

3. The combination with a shank, of a blade secured thereto having sharp upper and lower 70 edges, and ends, the ends being bent to provide hackers and pullers, substantially as shown and described.

4. The combination with a shank, having a head, and a seat at the juncture of said head and shank, of a blade secured to the head and resting upon the seat, said blade having sharp upper and lower edges and ends, which ends are bent substantially as and for the purpose 75 described. 80

5. The combination with a shank having a head, a seat and retaining flange, of a blade secured to the head resting upon the seat and behind the flange, said blade having sharp upper and lower edges and ends said ends being curved substantially as and for the purpose 85 described.

6. The combination with a shank of the head arranged thereon, the seat at the lower end of the head and the transverse rib at the upper end of the head, and the detachable reversible blade secured to the head between the seat and rib, said blade having sharp upper and lower edges and edged rounded ends, said ends being bent substantially as shown and 90 for the purpose described. 95

7. A blade having sharpened upper and lower edges, and sharpened and rounded ends said ends being bent back toward each other substantially as shown and described.

WALTER WATSON.
